UNITED STATES PATENT OFFICE.

HUGH H. HARRIS, OF ALEXANDRIA, VIRGINIA.

COLLAPSIBLE MECHANIC BENCH.

Application filed December 27, 1920. Serial No. 433,247.

To all whom it may concern:

Be it known that I, HUGH H. HARRIS, a citizen of the United States, residing at Alexandria, in the county of Arlington and State of Virginia, have invented certain new and useful Improvements in Collapsible Mechanic Benches, of which the following is a specification.

This invention relates to a portable or knock-down bench for mechanics. The object is to provide a bench which may be erected in a small room without causing injury to the interior of such a room, or to occupy excessive space.

Another object of the invention is to provide such a bench which is capable of being folded into a compact form, and when so folded to be readily carried upon the shoulder of a mechanic, or transported without objection on any common carrier; to this end the frame is preferably made of seasoned wood, such as oak, thereby giving maximum strength with a minimum amount of weight.

The combination and arrangement of contacting faces and connecting straps is such as to provide a rigid frame when in the operative position without adding excess weight to the device.

The bench is primarily for mechanics engaged in pipe fitting, such as plumbing, gas fitting, heating and electric work. It will be found extremely valuable on repair and remodeling work.

The frame in general is made of 2 x 4 inch material, although the exact size of the members forms no part of the invention, and does not limit it.

I attain these objects by the mechanism illustrated in the accompanying drawing, in which Fig. 1 is a perspective view of the bench in operative position.

Fig. 2, is a vertical section taken through the bench in its operative position.

Fig. 3, is an end view thereof. Fig. 4, is a view in the inoperative or folded position.

Similar numerals refer to similar parts throughout the several views.

The bench is in the form of a right triangle and is composed of a base member 1, an upright member 2, and a member 3, corresponding to the hypotenuse of the right triangle.

Members 1 and 3 are pivotally connected by a pair of strap members 4 mounted by bolts 5 engaging the respective frame mem-

bers. In the base member 1 a notch 6 is provided to serve as a seat and support for the lower or formed end of member 3. In this seat a pin or lug 7 may be provided to center the member 3 in the seat when the bench is in the operative position.

Similarly members 2 and 3 are connected by means of a notch 6', straps 4' and bolts 5'.

Experience has shown that a maximum of rigidity is obtained when the straps 4 and 4' form a right angle with their respective adjacent notched frame members.

By reference to Fig. 4 it will be observed that the arrangement of parts permits the folding of the members when the inoperative position is desired.

The connection between members 1 and 2 is of a detachable character. A bolt 7' passes transversely through base member 1. A slot 9 straddles this bolt on the medial line of the base member. Pivoted to the bolt in this slot is a strap 8. This strap is adapted to enter a slot 10 in the end of the member 2, when the device is inoperative position, as is shown in Fig. 2. A pin 11 is then passed through the bifurcations of member 2 and the strap 8. This locks the device in the operative position. Seating pins similar to member 7 prevent any relative motion between members 1 and 2. A chain 12 may be attached to pin 11 to prevent the loss thereof.

When it is desired to fold the bench, as in Fig. 4, pin 11 is withdrawn; member or leg 2 is folded between members or legs 1 and 3, and strap 8 is passed through opening 13 in member or leg 2 and opening 14 in member or leg 3, and pin 11 again passed through the opening in strap 8. By this arrangement no extra parts are needed to secure the device in the inoperative position. Mounted on member or leg 2 is a support 15 which may carry any suitable socket or universal joint 16 for the attachment of a brace 17. This brace may be attached to a wall or floor as necessity demands. In the folded position this brace lies along member or leg 1 and is secured by a chain 18.

The base member 1 is provided with suitable countersunk holes 19 through which lugs or bolts can be passed if additional securing means be desirable. Members or legs 2 and 3 are provided with a plurality of transversely extending bolts 20. The heads of these bolts are countersunk so that a smooth exterior surface is given to the mem-

ber or legs. These bolts are to strengthen the wood and prevent longitudinal splitting of the various members or legs. This feature will again be referred to.

5 Member or leg 2 is provided with a pocket 21 for carrying extra belts, nuts, etc. This member or leg is also provided with two holes 22 which are set at an angle to the faces of the member or leg. This angle is 10 such that a pipe or tool handle passed through the hole will be deflected away from member or leg 3. Also these angles provide sufficient slope to act as tool holders. The faces of these openings are scalloped or 15 "dished" out. This is also true of the openings 22 in member or leg 3. (Fig. 2.) These holes 22 are for the primary purpose of bending, offsetting, or straightening any sized pipe up to 1 inch. A straight pipe is 20 passed through one of these holes. Pressure is applied to the pipe and a bend made. Were the edges of the holes 22 sharp there would be a tendency to break or close the pipe; but by the provision of the rounded 25 shoulders a smooth bend can be accomplished. The bolts 20 are very desirable in preventing any tendency of the wood to split, while under the strain of the bending pipe. Several sizes of holes may be employed if desired. By having the openings 30 22 facing upward, pipe can be bent in a small room as the diagonal distance between the floor and ceiling may be taken advantage of.

In base member or leg 1 is found a pocket 35 24'. Directly over this pocket, and in a vertical continuation of its side walls, is another opening 23 in member or leg 3. These openings are in alignment so that a die-stock handle can be held in an up-right position. By this arrangement any 40 oil which might drip from the dies will be caught in pocket 24.

Provision is made for mounting a vise on member or leg 3 by providing a plurality of holes 24. Through these holes are 45 passed countersunk bolts 25. By providing a plurality of holes various sizes of vises may be used or adjustability in the height of a vise may be obtained. A suitable hook 26 is provided on the face of member or leg 3 for holding a pipe cutter. Likewise a pair of oppositely curved hooks 50 27 are provided along the side of member or leg 3 for holding a wrench. It is to be observed that the location and arrangement 55 of these hooks prevents any possible interference of the tools with one another.

At the upper end of member or leg 3 are found seats for two receptacles 28 and 29. 60 These receptacles are set at such an angle that they will be parallel to the floor when the bench is in its operative position. One receptacle is to secure an oil can and the other to secure white lead or "dope."

65 It will thus be seen that I have provided

a compact bench which furnishes all the bench purposes usually required on a job, and at the same time is capable of being easily and perfectly "knocked down," packed and carried.

If desired the various members or legs may be formed of metal. I am aware that numerous changes may be made in this work bench without departing from the spirit of the subjoined claims.

Having thus described my invention, what I claim and desire to secure by Letters Patent is:

1. A collapsible work bench comprising a frame composed of pivotally connected 80 members, which defines a right triangle when in the operative position, one side of said triangle being the base member of the bench.

2. In a collapsible work bench, a pivotally connected frame comprising a plurality of parts of substantially uniform dimensions and configuration, all of which in the operative position, are secured to each other by means of co-operating bolts, straps, 90 and nuts on the bolts, together with inter-fitting notches, and formed ends.

3. A collapsible work bench comprising a pivotally connected frame, certain of the members of said frame being provided with 95 notches, certain of the members of said frame being provided with formed ends to fit said notches, the frame forming a right triangle when in the operative position.

4. In a right angled collapsible work 100 bench, a base member having near one end a notch, a hypotenuse member having a formed end to co-operate with the notch in the base member, a second notch formed near the end of the hypotenuse member, a perpendicular member having a formed end engaging the notch of the hypotenuse member, a notch at its opposite end co-operating as a securing means with the base member, together with auxiliary bracing means. 110

5. In a collapsible work bench, a pivotally connected frame, certain of the members of said frame being notched, certain of said pivoted connections consisting of straps secured by bolts adjoining said 115 notches, said straps extending at substantially a right angle to said notched members.

6. In a collapsible work bench a pivotally connected frame, one of said pivotal 120 connections consisting of a metal strap fitting corresponding slots in two adjoined members, one end of said strap being secured to one member by a bolt and to the other member by a removable pin.

7. In a pivotally connected collapsible work bench, frame members provided with holes, one of said pivoted connections including a perforated metal strap, said strap being adapted to pass through said holes 130

and means operating with one of said perforations, to secure the device in collapsed position.

8. In a device of the character described, 5 a plurality of pivotally connected frame members, one of said members having a pocket formed therein, another of said members having a hole passing therethrough which comes into alignment with said 10 pocket when the device is in the operative position.

9. A collapsible work bench defining, in 15 its operative position a right angled triangle, provided at the apex with horizontal receptacles.

10. In a collapsible work bench a plurality of pivotally connected members, one of said members being provided with a plurality of bolts for adjustably securing 20 thereto a vise.

11. In a collapsible work bench a plu-

rality of pivotally connected members, a pair of such members meeting, in the operative position of the device, at an acute angle, one member being provided with a 25 plurality of openings set at an angle such that the openings tend to deflect an object passed through them away from the face of the second member.

12. A collapsible work bench, provided 30 with a plurality of pivotally connected members, one of said members being provided with a plurality of hooks whose bills extend in diverging relation to one another, whereby different styles of tools can be 35 held without interfering with each other.

In testimony whereof I affix my signature.

HUGH H. HARRIS.
